UNITED STATES PATENT OFFICE.

SAMUEL C. WILHITE, OF LOS ANGELES, CALIFORNIA, ASSIGNOR TO WILWHITE MACHINE WORKS, INC., OF LOS ANGELES, CALIFORNIA, A CORPORATION OF CALIFORNIA.

DESIGN FOR A WALL-BRACKET ELECTRICAL FIXTURE.

Application filed December 7, 1926. Serial No. 19,958. Term of patent 3½ years.

To all whom it may concern:

Be it known that I, SAMUEL C. WILHITE, a citizen of the United States, residing at Los Angeles, in the county of Los Angeles and State of California, have invented a new, original, and ornamental Design for a Wall-Bracket Electrical Fixture, of which the following is a specification, reference being had to the accompanying drawing, forming part thereof.

Fig. 1 is a front elevation of a wall bracket electrical fixture, showing my new design, only a portion of the surface finish of the

article being indicated in heavy lines, it being understood that the unshaded portion involves a repetition of that portion shown in heavy lines.

Fig. 2 is a diagrammatic top view thereof.
I claim:

The ornamental design for a wall bracket electrical fixture, as shown.

Signed at Los Angeles, in the county of Los Angeles, and State of California, this 26th day of November, 1926.

SAMUEL C. WILHITE.
